SURGE ARRESTER

Samuel Ruben, New Rochelle, N. Y., assignor to
Sirian Lamp Company, Newark, N. J., a corporation of Delaware

Application August 23, 1930, Serial No. 477,305

2 Claims. (Cl. 250—27.5)

This invention relates to surge arresters adapted to be used in electrical circuits to protect delicate apparatus from excess current.

One of the objects of the invention is to provide a simple apparatus which may be connected in any electrical circuit which will effectively prevent surges of current above a predetermined amount.

Another object of the invention is to provide a surge arrester which will lead away only the excess portion of current when a surge occurs in the line so that the surge will produce no appreciable effect in the circuit.

Other objects of the invention and objects relating particularly to the construction and assembly of the various parts will be apparent as the description of the invention proceeds.

The invention has been illustrated in the accompanying drawing in which:

Fig. 1 is a front elevational view of my improved surge arrester;

Fig. 2 is an enlarged longitudinal sectional view of one of the elements shown in Fig. 1; and

Fig. 3 is a front elevational view of a modified form of the construction.

Referring now more specifically to the drawing the invention is shown as comprising an envelope 10 of glass or other suitable material integrally formed with the usual press 11 for supporting the elements of the device. A pair of electron emitting elements 12 and 13 may have their lower ends mounted upon two support rods 14 and 15 which may be sealed in the press 11 and their upper ends welded to a connecting rod 16 which may be sealed in a glass bead 17. A support rod 18 may be sealed in the press 11 and may extend substantially axially of the envelope to the upper end thereof where it may be sealed in the bead 17. The support rod 18 may be provided with a plurality of cross members 19 which may extend outwardly with their ends pointed and terminating a short distance from the elements 12 and 13 as clearly indicated. Leading-in wires 20, 21, and 22 may be connected respectively to the support rods 14, 15, and 18.

The electron emitting elements 12 and 13 may each comprise a coil 23 (see Fig. 2) of resistance wire such as tungsten, molybdenum, tantalum, or nichrome and the outer surface of the coil may be coated with an electron emitting material 24 which may be any of the electron emitting materials well known in the art, such as the oxides of the metals of the alkali earth group or a mixture of these oxides.

The envelope 10 may be filled with an inert gas,

preferably one of the monatomic gases or mixtures of such gases, such as argon, neon, helium, krypton, or xenon, and if desired the conductivity may be increased by introducing a small amount of metal vapor such as the vapors of mercury, rubidium, or caesium.

The bulb is preferably flashed with magnesium provided in a small container 25 attached to a wire 26 which may in turn be attached to one of the support rods as the rod 14.

With the elements mounted upon the press and the press sealed in the envelope 10 as indicated in Fig. 1 the envelope may be connected in the usual manner with an exhaust pump and an oven placed over it to heat it to a temperature of 350 to 400° C. or to as high a temperature as the glass will stand without the glass deforming. A current may be also run through the filament to raise it to about 600° C. and the gases which are driven off from the filament and other parts of the lamp are withdrawn from the envelope by the vacuum pump. This process is continued until all of the gases driven off have been removed and a high vacuum of preferably .5 of a micron is obtained. The absence of gas may be determined by the lack of fluorescence when high tension current from an induction coil is directed against the walls of the bulb.

When no more gases are evident the filament current may be slowly increased to approximately 800° C. when it will have a bright red appearance which drives out the binder in the electron emitting material and other gases which may be present. When again no more gas is found in the bulb the oven may be raised and the filament heated for a moment to approximately 1200° C. or slightly less when more gases are driven out and drawn out of the bulb by the vacuum pump until the high vacuum is again obtained.

The pump may then be shut off and the filament current turned off and a slight amount of an inert gas such as neon at about $\frac{1}{2}$ mm. pressure may be admitted to the bulb and the filament current turned on again and gradually increased. Spots of localized discharge will then appear having a reddish color and will gradually increase and spread until a diffused bluish glow completely fills the bulb. This process appears to activate the electron emitting material and may be maintained until the discharge is uniform throughout the bulb which usually takes less than ten minutes. During this time the current on the filament should not be raised too high so that the coating will not be destroyed or

thrown off from the filament. If white discharge spots appear on the filament and support rods it is an indication that there are more gases or vapors within the bulb and the bulb should 5 again be exhausted and the whole process of activation repeated.

When the activation is completed the filament temperature may be raised to about 1400° C. and then the vacuum pump again connected and the 10 gas pumped out to remove any undesirable gas which may have been thrown off during the activation process.

When the high vacuum is again obtained the filament circuit may be disconnected, the filament current turned off, and 50 mm. of neon gas admitted into the bulb followed by about 150 mm. of argon. The bulb may then be sealed off and after the magnesium is flashed by external bombardment may be ready for use.

20 The metal vapor may be introduced into the bulb by placing a small quantity of a salt of the metal, such as the chloride, with the magnesium in the container 28. When the magnesium is heated with the salt it will react therewith to 25 liberate the free metal and form a salt of magnesium. The free metal will condense on the walls of the bulb to be vaporized again when the bulb is heated in use.

When such a device is connected in a circuit 30 the elements 12 and 13 are raised to electron emitting temperatures and emit electrons which appear to ionize the gas in the vicinity of the element forming a conducting path through which current will flow and which produces a region 35 of illumination like a halo around the element, as described in the co-pending application of Chester H. Braselton, Serial No. 459,048, filed June 3, 1930. The conducting path surrounding the elements 12 and 13 will carry additional current 40 and the cross-sectional area of this conducting path depends upon the amount of current flowing in the circuit. Hence, the members 19 are placed between the elements 12 and 13 close enough to each to touch the edge of the conductive area when the normal current is flowing 45 in the circuit. When a surge of current occurs the discharge around the elements 12 and 13 will increase in size and include the members 19 and as the leading-in wire 22 is connected to 50 ground there will be a flow of current through the members 18, the support rod 13, and the wire 22 and the additional current will be dissipated and will not be felt in the circuit. Thus 55 damage to electrical apparatus by a current surge may be prevented.

In Fig. 3 a modified form of the invention is illustrated in which electron emitting elements 27 and 28 similar to those already described may be mounted at their lower ends upon support 60 rods 29 and 30 respectively which may be sealed in the press 31 and at their upper ends upon a cross connector 32 which may be welded or otherwise attached to a support rod 33 mounted in the press 31 and positioned substantially on

the axis of the bulb. A rod 34 may be positioned adjacent the element 27 and may be provided with a plurality of metallic points 35 which are spaced a short distance from the element 27. The rod 34 may extend downwardly and may be sealed in the press between the support 29 and the center support 33. In like manner a support rod 36 may be provided adjacent the element 28. This rod may be also provided with a plurality of metal points 37 and may also extend downwardly to be sealed in the press between the center support rod 33 and the element support 30. Leading-in wires 38 and 39 may be attached to the support rods 29 and 30 while the rods 34 and 36 may have leading-in wires 40 and 41 respectively connected to them. These last two wires may be connected together and to ground.

The device thus constructed, when surrounded with the ionizable gas as already described in connection with Fig. 1, will operate in a similar manner, the points 35 and 37 intercepting the additional discharge from a surge of current and the addition current will ground with the result that the electrical apparatus is protected.

While I have shown a particular type of electron emitting element, other elements may be used, for instance a single straight wire coated with electron emitting material might be used or the material might be coated intermittently on said wire or on a coil, or the individual turns 30 of the coil may be coated leaving space between every two turns.

Many other modifications may be resorted to without departing from the spirit of the invention and I do not therefore desire to limit myself to what has been shown and described except as such limitations occur in the appended claims.

What I desire to claim is:

1. A surge arrester comprising an envelope, 40 a filamentary wire within said envelope, a coating of electron emitting material upon the surface of said wire, a mixture of 75% of argon and 25% of neon surrounding said wire and having a pressure of approximately 200 mm. of mercury, and an electrode positioned in the vicinity of said wire but separated therefrom by gaseous space, said electrode contacting with the luminous space formed about said wire when an excessive current flows therethrough. 50

2. A surge arrester comprising an envelope, a pair of substantially parallel electron emitting elements connected in series within said envelope, a conductor support positioned between said elements, a plurality of pointed electrodes on said support and extending into the vicinity of said elements, and an ionizable gas surrounding said elements and having a pressure of substantially 60 200 mm. of mercury, said electrode contacting with the luminous space formed about said elements when an excessive current flows therethrough. 55

SAMUEL RUBEN.
